DESIGN FOR A METAL TRAY

Louis M. Schnitzer, New York, N. Y.

Application May 24, 1939, Serial No. 85,175

Term of patent 3½ years

To all whom it may concern:

Be it known that I, Louis M. Schnitzer, a citizen of the United States and resident of New York city, in the county of New York and State of New York, have invented a new, original, and ornamental Design for Metal Trays, of which the following is a specification, reference being had to the accompanying drawing, forming a part thereof.

Fig. 1 is a top plan view of a metal tray, showing my new design.

Fig. 2 is a vertical sectional view of the same taken on the line 2—2 of Fig. 1.

Fig. 3 is an outside elevational view of the same.

I claim:

The ornamental design for a metal tray, as shown.

LOUIS M. SCHNITZER.
